APPARATUS FOR OIL WELL CEMENTING

Erd V. Crowell, Los Angeles, Calif.

Application June 17, 1935, Serial No. 27,041

33 Claims. (Cl. 166—1)

This invention relates generally to means for cementing oil wells, principally to shut out water, as well as to support and protect the casing; and is specifically directed to a novel form of valve which is utilized to perform the three-fold functions; first, of a float valve to float the casing in; second, as part of a cementing plug, to actuate valve means to open lateral ports through the wall of the casing; and third, to close the bore through the casing below said lateral ports, thus to deflect the cementing mixture therethrough. This application is a continuation-in-part of my application for patent, filed December 5, 1932, on which Patent No. 2,071,389 issued, 5 certain subject-matter thereof having been reserved for claiming herein. Other subject-matter of the present application has been claimed in my Patents No. 2,071,390 and No. 2,071,391. My copending applications, S. N. 133,413 and 10 S. N. 119,986, filed March 27, 1937 and Jan. 11, 1936, respectively, are continuations-in-part of the present application. Manipulation of the great weight of a lengthy string of casing necessary in deep wells usually requires the employment of one or more float valves, to assure positive closure of the lower end of the string to pressure outside thereof, thus to allow the casing to be floated by partial counteraction of its weight 15 by the density of the fluid in the well, thereby to relieve excessive strain on the derrick, elevator, etc., and it is generally conceded that in deep wells, where the investment is great and every precaution must be taken, it is good practice and cheap insurance to use more than one float 20 valve in a casing.

In the art of shutting off water in deep wells, prior to my invention, cement slurry, intended to be discharged by fluid pressure either through the bottom of the casing or through lateral ports 40 therein, has had to pass through the restrictive mechanism of one or more float valves. The considerable amount of time necessarily consumed in the process of mixing and pumping in, the increasing temperature encountered at great 45 depths, the friction of the heavy cement slurry passing through several thousand feet of casing, the consequent enormous pump pressure required combined with the thickening effect of the obstructions in the float valve tends to hasten coagulation or partial setting of the cementitious mixture and to prevent free flow thereof into recesses of the well bore around the casing shoe. Efforts to combat these difficulties have resulted 50 in experiments with streamlined float valves, designed to reduce friction on the cement, but which 55

have proved to be of such questionable value as to discourage the employment of any float valve structure and to consequently forego the many advantages of their use as outlined above.

It is a general object of the present invention to avoid the above-mentioned disadvantages by the provision of valvular means for floating a string of casing to position in a well bore, said means being adapted for use with conventional auxiliary float valve bodies, usually of lapideous material, and casing-shoe guides of similar composition, which after performing its functions as a float valve, by alteration of its position relative to a series of lateral ports in the casing, may be utilized to direct cementitious material, driven by fluid pressure in a substantially unobstructed bore of the casing, through said ports, thus to avoid passing any cement through a float valve. 5

A specific object of primary importance is to provide a float valve located above a series of lateral ports in a casing adapted to close the bore therethrough to pressure below said valve during preliminary positioning and circulation, and which, by means of a plug preceding a quantity of cement, inserted in the casing, may be released 10 to subsequently close the bore below the ports allowing continued pressure through the casing to discharge the cement through said ports. 20

Another object is the provision of lateral ports in a casing adapted by their shape to swirl cementitious material around the casing upon its discharge therefrom, thus to facilitate distribution of the material into recesses and cavities of the well bore and insure thorough circulation 25 around the casing. 30

It is a further object to provide a plug carrying means slidably fitting the well casing adapted to be forced by fluid pressure downwardly therethrough to actuate the float valve releasably supported in the well casing to open ports and close 40 the bore of the well casing below the ports while said pressure fluid by-passes the plug downwardly through the casing and out through the open ports. 45

It is a further object to provide, if desired, an indicator plug to be forced down the well casing by fluid pressure in back of a quantity of cement and adapted to seat above the point of discharge of the cement, to close the bore of the casing to fluid pressure thereabove, thus leaving the washed cement or tailings in the casing for subsequent removal by drilling tools. 50

It is a still further object of the invention to provide the discharge ports with auxiliary valvular means adapted to open by pressure of the 55

material discharged outwardly through the ports upon the closure of the bore of the casing therebelow, but adapted to prevent return flow of material into the casing from the surrounding well bore irrespective of the position of the indicator plug.

Still another object is the provision of a device, simple in construction, which may be utilized by operators of ordinary skill in the art to facilitate accurate discharge and distribution of cementing material outside of the casing.

With the foregoing and other objects in view my invention consists in certain novel features of construction and arrangement of parts which will be hereinafter more fully described and claimed, one embodiment being illustrated in the accompanying drawings, in which:

Fig. 1 is a view, in section and elevation, illustrating the various parts of my invention as positioned in a casing for lowering within the well bore.

Fig. 2 is an enlarged sectional view of the upper float valve assembly with the lower cement plug in operative position therewith.

Fig. 3 is a cross-sectional view taken on line 3—3 of Fig. 1;

Fig. 4 is a view of my invention similar to Fig. 1 showing the parts thereof as positioned upon the completion of the cementing operation;

Fig. 5 is an enlarged perspective view, partly cut away, of the lower plug and its releasable packer;

Fig. 6 is a sectional view illustrating a modified form of the assembly at the bottom of the casing in which a conventional form of float plug is substituted for the shoe guide depicted in Fig. 1.

Referring to the drawings in detail, the numerals of which indicate similar parts throughout the several views, 10 designates a section of well casing. A float valve assembly generally indicated by A, which is hereinafter more fully described, is mounted within a short pipe coupling 11 threaded to casing 10 having secured to its lower end a casing section 12. A casing shoe 13 is attached to the lower end of casing 12, having a series of lateral ports 14 extending through its wall at an angle with respect to the diameter of the shoe (Fig. 3), so that the forcible discharge of cement therefrom will swirl the cement around the casing, rather than directly against the wall of the well bore, thus avoiding uneven distribution of the cement. Each of ports 14 is normally maintained in closed position by a resilient flap valve 15 secured by suitable means to the outside of shoe 13 to permit the discharge of cement from the casing by driving pressure sufficient to open said valves, but preventing ingress through ports 14 upon release of said pressure by their automatic closure.

A shoe guide 16 of a type well known in the art, preferably constructed of concrete, or other lapideous material easily drilled out after the cementing operation is completed, is molded in the lower end of casing shoe 13, and has an open bore 17 through which said fluid may be circulated as required on its way down and subsequently, to remove obstructions and debris. The inner wall of shoe 13 may be spiralled or otherwise grooved to retain the shoe guide thus molded, as indicated at 18. A closure for lateral ports 14 on the inside of casing shoe is provided by a ring valve 19 slidably fitting the bore thereof and resiliently supported by a spiral

spring 20 which urges ring 19 against a series of studs 21 located in the bore of shoe 13 above said ring to limit upward movement thereof. The downward compression of spring 20 by means about to be described will permit fluid pressure to open valve 19 and enable circulation through ports 14.

The construction of the upper float valve assembly A forming a part of the essence of the present invention will now be described: The bore through pipe coupling 11 is provided with a valve body 22 of concrete or other lapideous material, which may be subsequently removed by drilling tools and is supported therein by being molded in grooves 23 formed on the inner bore of said section 11. The upper and lower edges of valve body 22 are beveled to form valve seats 24 and 25, respectively. A float valve is indicated by 26 having its upper face beveled at 26' to coincide with the bevel of seat 25 and its lower face pointed to close the bore through ring 19 as will be presently made obvious. Valve 26 is supported adjacent seat 25 by means of a shank 27 thereof extending upwardly into the bore of valve body 22 having a vertical slot 28 throughout its length. A pin 29 through the upper end of shank 27 supports a spring wire within slot 28 which is bowed outwardly on each side as indicated at 30a and 30b, which bowed portions converge at the base of the slot where the ends of said wire are turned back, projecting into holes 31—31 provided in each side of valve body 22 to form retaining fingers 32 and 33. The compression of the bowed portions 30a and 30b of said spring wire, by means later referred to, will force the lower ends thereof into slot 28 across each other, as indicated in Fig. 2, withdrawing their respective retaining fingers from holes 31—31, and releasing the float valve 26, for a purpose later to be explained.

Further description of the construction of my invention should be prefaced by a brief outline of necessary preliminary operation to enable a better understanding of the objects and functions of the various parts: The device is assembled with the fingers 32 and 33 resiliently supporting valve 26 adjacent its valve seat 25, lateral ports 14 being held in closed position by the upward urge of spring 20. While lowering the casing to position within the well bore, valve 26 will be closed due to pressure therebelow of fluid in the well, and will function at this stage of operation in the same manner as float valves of the prior art, thus permitting the casing to be floated to position, consequently avoiding excessive strain on the derrick and equipment. Circulation through the casing and the space outside thereof is established to remove detritus around the casing and permit the subsequent free flow of cementing material through ports 14, by the introduction into the casing of fluid under pressure which will open valve 26 slightly to enable the fluid to pass therebelow, through ring 19 and the bore of shoe guide 16, thence flowing upward around the casing.

After satisfactory circulation has been established, a traveling plug 34 is inserted into the casing on which a sufficient amount of cementitious material, the quantity of which will be determined by usual skill in the art, is also introduced therein. Plug 34 is of a diameter adapted to pass through the bore of valve body 22, and is bored to slidably fit over shank 27 of valve 26. The upper section of plug 34 is of reduced diameter forming a shoulder 35 on which a packer 36

of any suitable material is located. On top of the cement an indicator plug 37 is inserted, having a packer 38 located on a portion 39 of reduced diameter thereof, adapted to slidably engage the casing wall. Pressure exerted on indicator plug 37 will drive plug 34 over the shank 27 of valve 26 as indicated clearly in Fig. 2. The inner walls of hollow plug 34 will bring inward pressure to bear against the bowed spring portions 30a and 30b crossing the lower ends thereof and withdrawing fingers 32 and 33 from holes 31-31 as above generally described. Continued pressure through the casing will cause packer 36 to engage valve seat 24, which prevents its further downward movement; plug 34 however will thereafter become a part of valve 26 and is driven downwardly free of packer 36 forcing valve 26 through the bore of casing section 12 into the shoe 13, where the lower face of valve 26 will contact seat 40 provided on the upper rim of ring 19, compressing spring 20 and exposing lateral ports 14 to pressure thereabove. As the bore through shoe guide 16 is closed by the seating of valve 26 on ring 19, cement will be discharged through the ports 14 into the space outside thereof, until indicator plug 37 contacts seat 24 of valve body 22, closing the bore, whereupon pressure above plug 37 will build up causing the surface pump to labor or stall, thus indicating to the operator the progress of the cement slurry.

By maintaining a tight head on the well the cement is allowed to set and harden; the tailings of which cement left within the casing being later drilled out, together with lapideous valve body 22, plugs 34 and 37, float valve 26 and the shoe guide 16, in accord with general well known practice. The quantity of cement tailings it is desired to leave within the casing, variable with the length of pipe section 12, may be determined by usual skill in the art, being generally dependent upon the depth at which the cementing operation is performed.

A float plug of conventional construction (Fig. 6) may be substituted for shoe guide 16, to insure against leaks while floating the casing to position. It will also be noted that I have provided a modified form of ring valve support consisting of a plurality of studs 42 protruding from the inner wall of shoe guide 16 below ring 19 to support said ring adjacent the ports 14, said studs being composed of frangible material, capable of being sheared off by the pressure of valve 26 on the ring.

It will thus be seen that I have provided a device adapted to center and guide a casing in a well, having a float valve for the bore of the casing and lower end thereof, respectively, which combine and cooperate for use in a single string of casing to permit complete control of pressure differentials at all stages of operation, and to subsequently pump cement through a substantially unobstructed bore of the casing through ports therein. Free flow of cement around the casing will be facilitated by the automatic release of all float valve mechanism from the path of the cement, so as to present a substantially unobstructed bore through the casing to the discharge ports therein.

It will be obvious to those of skill in this art that various other changes in construction and arrangement of the several parts hereof may be made, such for instance, as the provision of vertical slots in place of holes 31-31, thus permitting a greater range of opening and closing movement of float valve 26; frangible pins might be

substituted for fingers 32 and 33; valve 26 may be made hollow, which construction, being of greater buoyance, will be more sensitive to reversals in pressure differentials, all without departing from the essence of my invention.

5

What I claim and desire to cover by Letters Patent is—

1. In an apparatus for cementing oil wells, a well casing, a valve body provided with a valve seat within said casing, a valve formed to fit said seat, means for releasably holding said valve from said valve seat, means actuated by fluid pressure to release said valve, and fluid pressure means to force said valve to and upon its said seat.

2. In an apparatus of the character described, 15 a well casing, a pair of float plug bodies held in spaced relation in said casing, each of said float plug bodies being provided with a valve seat facing that of the other, a float valve releasably associated with one of said seats and adapted to 20 close the bore of said casing to pressure from below by contact with said seat, means to release said valve with respect to said seat and pressure means to move said valve to its oppositely facing seat in the other of said float plug bodies to close 25 the bore through said casing to pressure from above.

3. In an apparatus for cementing oil wells, a well casing, a valve body in said casing having a circular bore, a valve seat in said bore, a float valve resiliently and releasably supported adjacent said valve body and adapted to close said valve by contact with said seat, and means actuated by fluid pressure to release said valve from 30 operative relationship with said valve seat.

4. In an apparatus of the character described, 40 a well casing, a plurality of ports in said casing, a float plug in said casing below said ports, a valve seat in said float plug, a float valve releasably supported above said ports, means to release said valve to close the bore through said float plug to pressure within the casing, and valve means normally closing said ports adapted to be opened by pressure from within the casing.

5. In an apparatus for cementing oil wells, a well casing, a float plug in said well casing below a port therethrough, a valve body in said casing above said port, a float valve in operative relationship with said valve body, and means actuated by fluid pressure to compel said float valve 50 to close the bore of said float plug.

6. In an apparatus of the character described, 55 a well casing, a port through said casing disposed at an angle relative to the diameter thereof, a valve body in said casing above said port, a float valve operatively associated with said valve body, and means to compel said valve to close the bore through the casing below said port.

7. In an apparatus of the character described, 60 a well casing, a lateral port through said casing, valvular means for said port, a float valve releasably held in said casing above said port, means actuated by fluid pressure to release said float valve and to successively actuate it to close 65 the bore through the casing and expose said port to fluid pressure thereabove within the casing.

8. In a cementing apparatus, a well casing, a valve body within said casing, a float valve releasably suspended with relation to said valve body, a plug adapted for actuation by fluid pressure to release suspension of said float valve with respect to said valve body, and an indicator plug adapted to seat on said valve body.

9. In an apparatus of the character described, 75

- 5 a well casing having a port therein, a valve body above said port, a valve releasably suspended adjacent said valve body to close the bore to pressure therebelow, and means to release said 5 valve to close the bore below the port.
- 10 10. In an apparatus of the character described, a well casing having a port therein, a float valve within the casing above said port, and means to move said float valve to close the bore below the 10 port.
- 15 11. In an apparatus of the character described, a well casing having a port therein, a float valve within the casing above said port, and means to open the bore through said float valve by pressure 15 from above and close the bore below said port.
- 20 12. In a device of the character described, a well casing, a lateral port in said casing, a float valve resiliently supported in the bore of said 20 casing adjacent said port, and a valve body for said float valve above and below said port.
- 25 13. In a device of the character described, a well casing, a lateral port in said casing, a float valve resiliently supported in the bore of said 25 casing adjacent said port, a valve body for said float valve above and below said port, and a plug actuated by fluid pressure to compel said valve to contact said lower valve body to close the bore below said port.
- 30 14. In a device of the character described, a well casing shoe, a port in said casing shoe, a valve body above and below said port, a valve adapted to seat on either of said valve bodies, resilient means normally urging said valve 30 against its upper seat and means actuated by fluid pressure to compel said valve to seat below said port.
- 35 15. In a device of the character described, a well casing, a port in said casing, a valve within 40 said casing adapted for control by fluid pressure to close the bore through said casing above or below said port, a plug carrying a packer adapted to slidably engage the wall of the casing to close the bore thereof, and a seat for said plug above 45 said port.
- 40 16. In a device of the character described, a well casing, a pair of annular valve seats spaced apart in the bore of said casing, a valve variably supported between said seats, and a lateral port 50 in the casing between said valve seats bored at an angle with respect to the diameter of the casing to permit fluid discharged therefrom to be 55 swirled around the casing.
- 45 17. In a device of the character described, a well casing, a pair of annular valve seats spaced apart in the bore of said casing, a valve variably supported between said seats, and a lateral port 60 in the casing between said valve seats bored at an angle with respect to the diameter of the casing, and variable closure means for said port adapted when opened by fluid pressure to deflect said fluid around said casing.
- 55 18. In an apparatus of the character described, a well casing, a valve body within said casing having an upwardly-directed shoulder, a float valve, resilient means connected with said float valve to contact said shoulder to support said valve relative to said valve body, and means to withdraw said resilient means from support by 65 said shoulder.
- 60 19. In an apparatus of the character described, a well casing, a valve body within said casing having an upwardly-directed shoulder, a float valve, resilient means connected with said float 70 valve to contact said shoulder to support said 75 valve to contact said shoulder to support said
- valve relative to said valve body, a plug adapted for actuation by fluid pressure to withdraw said resilient means from support by said shoulder.
20. In a device of the character described, well casing having a series of ports, valvular means normally closing the ports to prevent the egress of fluid from said ports, a float plug at the lower end of the casing, a float valve releasably supported in the bore of the casing above the ports to close the bore thereabove to pressure at the 10 ports, means to release and compel said float valve to open said ports and close the bore of the casing below the ports, thus to deflect the flow of said pressure fluid outwardly through the ports.
21. A device of the character set forth comprising a tubular body, means for connecting said body to a well tubing for forming a continuation of the latter and for lowering into a well with said well tubing, a destructible valve seat at one 20 end of the body, a valve means for permitting seal forming material to pass through the body and form a seal between the body and walls of the well, a check valve seat carried by the first-mentioned means, a valve located between the 25 valve seats and adapted to engage the first-named seat during the placing in and passing of the seal forming material from the body, means for temporarily supporting the valve adjacent to the second-named seat to act as a check valve 30 for preventing the pressure in the body passing to the well tubing during the lowering of the well tubing, and means for dislodging the valve from its temporary position.
22. In a device of the character described, a 35 well casing, a lateral port in said casing, a float valve resiliently supported in the bore of said casing adjacent said port, a valve body for said float valve above and below said port, and a plug to release said valve to permit it to contact said 40 lower valve body to close the bore below said port.
23. In combination, a string of casing for a well bore having a port in its side wall, means, normally closing the port to communication with the bore of the casing thereabove, adapted to be 45 lowered in the casing and thereby open the port to the bore of the casing thereabove, and means, including a member adapted to by-pass fluid in the casing, to actuate said first-mentioned means to cause the communication of said port and the 50 bore of the casing above said first-mentioned means.
24. In a well cementing apparatus, a string of casing having a lateral port therein, said string above said port being adapted to retain a column 55 of fluid extending to the well surface, a valve in the casing normally closing said port to communication with the bore of the casing above the valve, and means comprising a member adapted to by-pass fluid in the casing to move said valve below the port and thereby cause communication of said port with the bore of the casing above said means.
25. In combination, a string of casing for a well bore having a lateral port therein, valvular means normally closing the port to pressure in the casing above said valvular means but movable downwardly to open the port to pressure thereabove, and means, comprising a member adapted to upwardly by-pass fluid in the casing, 70 to actuate said valvular means to open said port to pressure thereabove.
26. In a device of the character described, a ported well casing, a float valve adapted to close the bore of the casing above the ports, and 75

means actuated by fluid pressure above the valve to compel said valve to close the bore below the port to pressure thereabove.

27. A ported well casing, a pair of annular valve bodies in said casing, a valve variably supported between said valve bodies, and a plug actuated by fluid pressure to maintain said valve on said lower body.

28. A ported well casing, valvular means inside said casing closing the ports, a float valve resiliently supported therein above the ports, and a plug adapted to be driven by and moved concurrently with pressure fluid downwardly through the casing for releasing said float valve to seat on said valvular means thus to open the ports and close the bore of the casing below the ports.

29. Well casing having a bore for the passage of pressure fluid downwardly therethrough, peripheral ports in said casing, a float valve resiliently supported in the bore of said casing above the ports in combination with a float valve for the lower end thereof, means comprising said pressure fluid, and a plug actuated thereby for releasing said first named float valve for opening the ports and closing the bore of the casing below the ports.

30. Well casing having a bore for the passage of pressure fluid downwardly therethrough, peripheral ports in said casing, a float valve resiliently supported in the bore of said casing above the ports in combination with a float valve for the lower end thereof, valvular means inside said casing tending normally to maintain closure of said ports longitudinally slidably therein to open the ports and forming a seat for the first named

float valve, and a plug actuated by said pressure fluid for releasing said first named float valve to seat on said valvular means thus to open the ports and close the bore of the casing below the ports.

31. In a device of the character described, the combination of: an outer ported member adapted to be connected to the lower end of a string of well casing, an inner sleeve valve in said member tending normally to maintain closure of said ports, a plug of lapideous material secured in the lower end of said member tapered inwardly and downwardly to form a guiding end, a passageway formed centrally and longitudinally through said plug, a float valve closing the bore of said passageway to pressure therebelow, a second float valve resiliently supported in said casing above said ports, and a plug actuated by pressure fluid to release said second named float valve to seat upon said sleeve valve for opening the ports and closing the bore of said passageway to pressure thereabove.

32. In a cementing apparatus, a ported well casing, a valve seat in said casing, a valve adapted to contact said seat by pressure from below, and means actuated by fluid pressure to displace said valve with respect to said seat.

33. In a cementing apparatus, a ported well casing, a valve above the port in said casing adapted to close the bore of the casing to pressure therebelow, and a plug actuated by fluid pressure to move said valve to the opposite side of said port.

ERD V. CROWELL.
